CLUTCH MECHANISM

Gordon C. File, Buchanan, Mich.

Application November 9, 1931. Serial No. 573,962

6 Claims. (CL 192—53)

My invention relates to improvements in clutch mechanisms, and it consists in the combinations, constructions, and arrangements herein described and claimed.

5 An object of my invention is to provide certain novel improvements in the form of my invention embodied in my application for patent, Serial No. 400,911.

A further object of my invention is to provide 10 novel means in a transmission mechanism whereby the speed ratio of the driven shaft with respect to the driving shaft may be changed without clashing the gears.

A further object is to provide novel means in 15 a transmission mechanism whereby the gears may be disposed in continuous mesh.

A further object is to provide novel means in 20 a transmission mechanism for synchronizing the driven shaft with the driving gears preliminary to the changing of speeds.

A further object is to provide a construction which is simple, durable, positive in operation, and efficient for the purpose intended.

Other objects and advantages will appear in 25 the following specification, and the novel features of the invention will be particularly pointed out in the appended claims.

My invention is illustrated in the accompanying drawings, forming part of this application, 30 in which

Figure 1 is a vertical sectional view of a transmission mechanism embodying my invention,

Figure 2 is an isometric view of the clutch element shown in Figure 1 connected with the 35 driving shaft,

Figure 3 is an isometric view of a clutch element shown in Figure 1 adapted for locking engagement with the clutch element shown in Figure 2,

40 Figure 4 is a view in elevation of a face of the clutch element shown in Figure 3.

Figure 5 is a side elevation of the clutch element shown in Figures 3 and 4, a portion thereof being shown in section,

45 Figure 6 is a side elevation of the clutch element shown in Figure 2, a portion of the driving shaft with which it is connected being shown in section,

50 Figure 7 is a view in elevation of the face of the clutch element shown in Figures 2 and 6,

Figure 8 is a vertical sectional view of the actuating lever and associated mechanism, portions thereof being shown in elevation,

55 Figure 9 is a horizontal sectional view of the

structure shown in Figure 8, portions thereof being shown in elevation,

Figure 10 is an elevational view partly in section of another form of my invention,

Figure 11 is an isometric view of the clutch 60 element shown in Figure 10 connected with the driving shaft,

Figure 12 is an isometric view of a clutch 65 element shown in Figure 10 adapted for locking engagement with the clutch element shown in Figure 11,

Figure 13 is a view in elevation of a face of the clutch element shown in Figure 12,

Figure 14 is a side elevation of the clutch element shown in Figures 12 and 13, 70

Figure 15 is a side elevation of the clutch element shown in Figure 11, a portion of the driving shaft being shown in section,

Figure 16 is a view in elevation of the face of the clutch element shown in Figures 11 and 75 15, and

Figure 17 is a perspective view of the friction clutch member and the locking clutch member with which it is operatively connected.

In carrying out my invention, I provide a 80 transmission housing 1 as shown in Figure 1. A driving shaft 2 extends within the housing and is provided with a gear portion 3 and a clutch-engaging portion 4. A driven shaft 5 is in axial alignment with the driving shaft 2. The driving shaft 2 is journaled for receiving an end 6 of the driven shaft 5. The other end of the driven shaft extends through the housing in which it is mounted and is operatively connected to a drive shaft, not shown, the same 85 being old in the art. A gear 7 is rotatably mounted on the shaft 5 and is provided with a clutch-engaging portion 8. A gear 9 is slidably and non-rotatably mounted on the shaft 5 and is provided with a hub portion 10 having an annular recess 10' for receiving the forked end portion of an actuating arm 11.

Integral gears 12, 13, 14, and 15 are rotatably mounted on an auxiliary shaft 16 which, in turn, is mounted in the housing 1. The gears 12 100 and 13 are in continuous mesh with the gears 3 and 7, respectively. The gear 9 is adapted for being moved into operative relation with either of the gears 14 or 15.

A clutch mechanism 17 is mounted on the driven shaft 5 and is slideable and non-rotatable with respect to said shaft 5. The clutch mechanism is positioned between the clutch-engaging portions 4 and 8 of the driving shaft 2 and the gear 7, respectively. The clutch mechanism 17 105

comprises a locking clutch member 18 and friction clutch members 19 and 19' slideable and non-rotatable with respect to each other. The specific construction of the clutch members 18 and 19 and the clutch-engaging portions 4 and 8 will be hereinafter explained in detail. As shown in Figures 1 and 9 a pair of parallel and spaced-apart actuating rods 20 and 21 is slidably disposed in the top portion 22 of the housing 1. A pair of oppositely positioned lever-engaging arms 23 and 24 is fixedly connected with the actuating rods 20 and 21, respectively, and is provided with recesses 25, 25' for receiving the end 26 of a gear shift lever 27. The lever arm 23 is provided with an extending portion 28 having a forked end portion 29 receivable in an annular recess 30 of the clutch member 18. A pair of actuating arms 31 and 31' is slidably mounted on the rod 20 on opposite sides of the lever-engaging arm 23. The actuating arms are limited in their movements with respect to the rod 20 by means of pins 32 connected with the rod 20 and receivable in recesses 33 in the end of the arms 31 and 31'. Spring members 34 and 34' are disposed on the rod 20 and are positioned between the lever arm 23 and the actuating arms 31 and 31'.

The arms 31 and 31' are provided with forked extensions 35 receivable in annular recesses 36 of the clutch members 19 and 19', respectively. The arm 11 is fixedly connected with the slideable rod 21.

It will be noted on referring to Figure 9 that the rods 20 and 21 are provided with arcuate-shaped recesses 37 for receiving spring pressed balls 38. Each of the rods 20 and 21 is further provided with an arcuate shaped recess 39 for receiving an end of a locking bar 40 slidably disposed in a transverse portion 41 of the top portion 22 of the housing 1.

The constructions of the clutch-engaging portions 4 and 8 are identical except that the flange portions thereof are oppositely positioned and therefore a description of one will suffice for both. The clutch-engaging portion 4 comprises a circular base portion 42 which, in this instance, is integral with the driving shaft 2. The base portion in connection with the clutch-engaging portion 8 forms a part of the gear 7. The base portion 42 has a flat face 43 disposed in a plane at right angles to the axis of the driving and driven shafts. The face of the base portion is provided with a pair of diametrically opposed and transversely extending arcuate-shaped flange portions 44 positioned adjoining the periphery of the base portion with which the outer surfaces of said flange portions join. The flange portions each comprise a lower raised portion 45 and a higher raised portion 46. The juncture of the higher raised portions with the lower raised portions provides a pair of oppositely disposed faces 47. The ends of the higher raised portions 46 provide a pair of oppositely disposed driving faces 48 and the ends of the lower raised portions provide a pair of oppositely disposed faces 49. All of the oppositely disposed faces are positioned at substantially right angles to the face 43.

The lower raised portions 45 and the higher raised portions 46 are respectively provided with faces 50 and 51 which are disposed in substantially parallel planes with respect to each other and the face 43 of the base portion 42. The outside surfaces of the flange portions 44 are tapered from the base portion 42 toward the

axis of the driven shaft 5 for providing beveled surfaces 52.

As shown in Figure 1 the shaft 5 is provided with splines 53. The locking clutch member 18 is slidably mounted on the shaft 5 and is held against rotation with respect to said shaft by means of integral spline portions 54 receivable in the splines 53 of the shaft. As shown in Figure 3 the locking clutch member comprises a pair of integral clutch portions 55 and 55'. The portions 55 and 55' are adapted for engagement with the clutch-engaging portions 4 and 8, respectively, and, since they have a common construction, it is believed that a description of the construction of the clutch portion 55 will suffice for both.

The clutch portion 55 is provided with a plane face 56 disposed at right angles to the axis of the driven shaft 5. The clutch portion 55 is further provided with a pair of oppositely disposed and radially extending peripheral projecting portions 57. The projecting portions 57 provide a pair of shoulders 58 and another pair of shoulders 59. The clutch portion 55 is further provided with a pair of oppositely disposed and radially extending peripheral flange portions 60 positioned between the shoulders 58 and 59 of the projecting portions 57.

The flange portions 60 are positioned from the face 56 a distance substantially equal to the difference in height between the portions 45 and 46 of the flange portions 44 of the clutch-engaging portion 4. The flange portions 60 are also positioned a sufficient distance from the shoulders 59 for receiving the portions 46 of the flange portions 44 therebetween and are provided with shoulder portions 60' for engaging the faces 47 of the flange portions 46. The shoulders 58 and 59 of the projecting portions 57 are spaced a sufficient distance apart for receiving the flange portions 44 therebetween and the faces 48 and 49 of the flange portions 44 are spaced a sufficient distance apart for receiving the projecting portions 57 therebetween. The projecting portions 57 are provided with splines 61 for receiving spline portions 62 of the friction clutch member 19, as shown in Figure 17.

The friction clutch member 19 is provided with an annular projecting flange portion 63 having an inner surface 64 beveled at substantially the same angle as the beveled surface 52 of the flange portions 44. The beveled surface 64 normally overlaps the beveled surface 52 in a slightly spaced-apart position whereby the friction clutch member 19 may be slidably and non-rotatably connected with the locking clutch member 18.

From the foregoing description of the various parts of the device, the operation thereof may be readily understood.

When the shift lever 27 is moved into engagement with the arm 24 shown in Figure 9, the shift lever may then be actuated for moving the rod 21 whereby the gear 9 may be moved into operative connection with the gear 14 or the gear 15, depending on whether it is desired to have the transmission operate in low or reverse speeds, respectively.

A clutch mechanism of any suitable type not shown is operatively associated with the source of power and the driving shaft 2 whereby the driving shaft 2 may be disconnected from the source of power.

It will be noted that when the rod 21 is moved

the locking bar 40 is moved into the recess 39 of the rod 20 thereby locking the rod 20 against movement while the gear 9 is operatively connected with the gear 14 or the gear 15. The 5 spring pressed ball 38 associated with the rod 21 holds the rod in its shifted position.

After the shift lever 27 is actuated for returning the rod 21 to its normal position shown in Figure 9, at which time the gear 9 is disposed in 10 its neutral position shown in Figure 1, the rod 20 may be moved by moving the shift lever 27 into engagement with the arm 23 and then actuating the shift lever.

When the rod 20 is actuated the transmission 15 may operate in second or third speeds depending on the direction in which the rod 20 is moved. Let us assume that it is desired to have the transmission operate in third speed. The shift lever 20 27 is first moved into engagement with the arm 23 and then actuated for moving the arm 23 and the rod 20 in the direction of the arrow 65 in Figure 1. The movements of the arm 23 are 25 practically continuous but are divided into two stages for the sake of clearness. As the arm 23 begins its movement during the first stage the pressure on the spring 34 by the arm is transmitted to the actuating arm 31 for moving the friction clutch member 19 whereby the annular flange portion 63 thereof may be moved into 30 frictional engagement with the beveled faces 52 of the flange portions 44 associated with the clutch member 4.

As the clutch mechanism associated with the 35 source of power and the driving shaft 2 does not have to be actuated prior to shifting the transmission mechanism into second or third speed positions the clutch member 4 may be rotating when the flange portion 63 of the friction clutch member 19 is moved into engagement with the 40 flange portions 44. If the shaft 2 is rotating, its motion is transmitted to the driven shaft 5 by reason of the friction clutch member 19 being splined on the projecting portions 57 of the locking clutch member 18 and the locking clutch member 45 being in turn splined on the shaft 5. Thus it will be seen that the coaction of the several elements tends to synchronize the rotation of the driven shaft 5 with the driving shaft during the first portion of the movement of the arm 23 and the rod 20. In view of the fact that a 50 load is carried by the shaft 5 there will be a drag on the shaft thereby tending to cause the friction clutch member 19 to slip slightly with respect to the flange portions 44. This slipping action will result in the driving shaft 2 rotating slightly faster than the driven shaft 5 for a short time until the driven shaft 5 gains momentum.

It will be noted on referring to Figure 1 that 55 when the arm 23 and the rod 20 are moved the extending portion 28 of the arm 23 is also moved for actuating the locking clutch member 18. The locking clutch member 18 is positioned at a sufficient distance from the clutch member 4 so that it will not be moved into engagement there- 60 with until after the clutch member 19 is moved into engagement with the flange portions 44. The clutch member 18 is, however, moved with respect to the shaft 5 during the first stage of the movement of the arm 23. It will be noted 65 that although the friction clutch member 19 has been moved to its extreme position by reason of its engagement with the flange portions 44, the arm 23 and the shaft 20 can continue their movements because of the arm 31 being slidably 70 mounted on the shaft 20.

The movement of the arm 23 during the second stage moves the faces 66 of the projecting portions 57 of the locking clutch member 18 into engagement with one of the faces 51, 50, 43 of the clutch member 4, depending on the 80 relative positions of the clutch members 4 and 18. Let us assume for the purpose of completely describing the operation of the device that the faces 66 engage the faces 51 of the higher raised portions 46. Because of the fact that the driving shaft 2 may be rotating at a slightly greater speed than the driven shaft 5 the faces 51 will pass over the faces 66 until the faces 51 of the higher raised portions 46 pass by the shoulders 58 of the projecting portions 57, at 85 which time, because of continued pressure on the arm 23, the faces 51 may move into engagement with peripheral flange portions 60. The faces 50 of the lower raised portions 45 move into engagement with the faces 66 simultaneously with the engagement of the higher raised portions 46 with the flange portions 60. The higher raised portions 46 may or may not engage the flange portions 60 as the lower flange portions 45 may properly position the higher raised portions in their proper overlapping relationship with respect to the shoulders 59.

Continued rotation of the clutch member 4 with respect to the clutch member 18 moves the raised portions 46 along the flange portions 60 until the shoulders 48 of the higher raised portions 46 abut the shoulders 59 of the projecting portions 57 and the shoulders 49 of the lower raised portions 45 pass by the faces 58 of the projecting portions 57.

After the shoulders 48 engage the shoulders 59 continued pressure on the arm 23 moves the face 43 of the clutch member 4 into engagement with the face 56 of the clutch member 18 at which time the higher raised flange portions 46 will be positioned between the shoulders 59 and 60 and the shoulders 49 of the lower flange portions 45 will be positioned abutting the shoulders 58, at which time the clutch members 4 and 18 will be in complete locking engagement and the arm 23 and the rod 20 will have reached their extreme shifted positions. At this time the spring 34 will be compressed between the arms 23 and 31 and the opening 37' of the rod 20 will be in position for receiving the ball 38. The ball 38 however is not sufficient to retain the rod 20 in the shifted position as the action of the compressed spring 34 will force the ball 38 out of the opening 37'. In order 115 to lock the arm 23 in its shifted positions I provide a projecting member 67 connected with the top portion 22 of the housing 1 as shown in Figure 8. The lever rod 27 is provided with a pair of spaced-apart lug portions 68 integral therewith. The lug portions are provided with aligned openings therethrough for receiving a locking rod 69 slidable with respect to the lug portions 68. The locking rod 69 has its lower end 70 extending beneath the lowermost lug 120 portion 68, the extending portion being normally positioned adjacent the end of the projecting member 67. The locking rod 69 is provided with a flange portion 71 positioned between the lug portions 68 and normally positioned on the lowermost lug portion. A spring 72 is disposed on the rod 69 and is positioned between the flange portion 71 and the uppermost lug portion 68. The openings in the lug portions 68 through 125 which the locking rod 69 extends are sufficiently

130

135

140

145

150

large to permit the rod to have a certain amount of play.

The top end of the rod is pivotally connected with an actuating handle 73 which, in turn, is pivotally connected with the lever arm 27 and is positioned adjacent a knob 74 connected with the top of the lever arm 27.

When moving the lever arm 27 for shifting the rod 21 the actuating handle 73 is not operated.

- 10 When it is desired to shift the transmission into second or third speeds the actuating handle 73 is first moved for lifting the locking rod 69 thereby permitting the end portion 26 of the shift lever 27 to be moved into the recess 25 of the arm 23 without the projecting member 67 engaging the end 70 of the locking rod 69 and thereby interfering with the moving of the shift lever 27. When the end portion 26 of the gear shift lever 27 is positioned in the recess 20 25' the end 70 of the locking rod 69 is positioned in engagement with the top side of the projecting portion 67. As the shift lever 27 is shifted for moving the arm 23, the end 70 of the locking rod moves along the top of the projecting portion 25 until the clutch members 4 and 18 are moved into locking engagement, at which time the end portion 70 of the locking rod 69 moves off an edge of the projecting portion 67 and engages a side thereof thereby locking the clutch members in engagement. When it is desired to shift the lever 27 to another position the actuating handle is again operated for moving the end portion 70 of the locking rod 69 out of engagement with the projecting portion 67 whereby 30 the lever 27 may be shifted.

In Figures 10 to 16, inclusive, I have shown another form of my invention. In this form of my invention I provide a clutch-engaging member 75 which is associated with a driving shaft

- 40 76 in the same manner as the clutch-engaging member 4 is associated with the driving shaft 2. A similar clutch-engaging member 77 is likewise associated with a second speed gear 78 which is mounted on a driven shaft 79 in the same manner as the gear 7 is mounted on the driven shaft 5. A movable clutch member 80 is slidably and nonrotatably mounted on the driven shaft in the same manner as the clutch member 18 is mounted on the shaft 5. The 45 clutch member 80 is positioned between the clutch members 75 and 77. In view of the fact that the clutch-engaging members 75 and 77 are similar except that the flange portions thereof are oppositely disposed a description of the clutch-engaging member 75 will suffice for both. The clutch-engaging member 75 is similar to the clutch-engaging portion 4 and comprises a base portion 81 which, in this case, is integral with the shaft 76. The base portion 50 of the clutch-engaging member 77 comprises a part of the gear 78. The base portion 81 is provided with a pair of oppositely disposed arcuate-shaped flange portions 82 which are similar to the flange portions 44 in that they comprise lower raised portions 83 which, in turn, are provided with higher raised portions 84. The flange portions 82 provide shoulders 85, 86, and 87. The base portion 81 and the lower raised portions 83 are provided with peripheral beveled faces 88 which are common to both in that the beveled faces of the lower raised portions are a continuation of the beveled faces of the base portion. The outer faces of the higher raised portions 84 are set in from the beveled faces 88 65 as shown in Figure 11.
- 70
- 75
- 70
- 75

The clutch member 80 is similar to the clutch member 18 to the extent that it comprises a pair of clutch portions 89 and 89' which are arranged for operative relationship with the clutch-engaging portions 75 and 77, respectively. 80 As both of the clutch portions and their respective parts are the same a description of the clutch portion 89 and its associated portions will, it is believed, be found sufficient. The clutch portion 89 is provided with a pair of oppositely disposed and radially extending peripheral flange portions 90 which comprise in part transversely extending arcuate-shaped flange portions 91 having beveled inner faces 92 conforming substantially to the beveled faces 88 of the clutch-engaging portions 75 and 77. Each of the flange portions 91 is provided with shoulders 93 and 94 which are substantially diametrically opposed with respect to the corresponding shoulders of the opposed flange portion 91. 90 95

On referring to Figure 11 it will be noted that the adjacent shoulders 85 and 87 of the opposed flanged portions 82 are spaced a sufficient distance apart for receiving the flange portions 90 of the clutch member 80 therebetween, and 100 that portions of the base portion 81 positioned between the adjacent shoulders 85 and 87 of the flange portions 82 is cut away for receiving the flange portions 91, whereby the flange portions 90 may not be prevented from being positioned 105 between the adjacent shoulders 85 and 87. The flange portions 91 are normally disposed in overlapping and slightly spaced-apart positions with respect to the flange portions 82 with which they are adapted for engagement as shown in Figure 10. A forked arm 95 is mounted on a shift rod 96 which is slidably disposed in the top 22' of the transmission housing 1'. The arm 95 is connected with the clutch member 80 whereby the same may be shifted. 110 115

In the latter form of my invention I have dispensed with the locking rod 69 and its associated mechanism. I have also eliminated the arms 31 and 31', together with the springs 34 and 34'. In this latter form of my device the 120 transmission is shifted into low and reverse speeds in the same manner as has been described concerning the first form of my device.

Let us assume that it is desired to shift the transmission into third speed position. The 125 shift lever 97 is first moved for shifting the rod 96 in the direction of the arrow 98 in Figure 10 whereby the arm 95 may be shifted. As the arm 95 is moved faces 99 of the flange portions 90 of the clutch member 80 engage 130 faces 100 of the higher raised portions 84, see Figures 10 and 11. As the clutch-engaging member 75 rotates, the higher raised portions 84 move along the faces 99 of the clutch member until the shoulder portions 86 pass by 135 the shoulder portions 93. Contained pressure on the shift lever then continues the movement of the clutch member 80 towards the clutch-engaging member 75 until the beveled faces 92 of the clutch member 80 frictionally engage the 140 beveled faces 88 of the clutch-engaging member 75. The engagement of the beveled faces will cause the clutch member 80 to be rotated which, in turn, will cause the driven shaft to be rotated thereby tending to synchronize the rotation of 145 the driven shaft with the driving shaft. Any resistance of the driven shaft to the driving shaft such as may be caused by a load being connected with the driven shaft will cause slippage between the beveled faces 88 and 92 150

which will result in the clutch-engaging member 75 rotating slightly faster than the clutch member 80. The clutch-engaging member 75 may rotate until the shoulders 85 of the clutch-engaging member 75 abut the shoulders 94 of the clutch member 80, at which time the beveled faces 92 of the clutch member 80 will have moved out of engagement with the beveled faces 88 of the clutch-engaging member 75.

10 Continued pressure on the shift lever will then move the flange portions 90 of the clutch member 80 between the shoulder portions 85 and 87 of the clutch-engaging member 75. At the same time the higher raised portions 84 will be positioned between the flange portions 90 and the flange portions 101 of the clutch member 80, the shoulders 86 of the higher raised portion 84 being in abutting relationship with the shoulders 102 of the flange portions 101.

15 When shifting transmission mechanisms from third speed to second speed position it is merely necessary to actuate a shift lever for moving the clutch member 80 into engagement with the clutch-engaging member 77 associated with the second speed gear 78, the operation being the same as has been described regarding the engagement of the clutch member 80 with the clutch-engaging member 75.

Thus it will be seen that in both forms of my invention the driven shaft may be first rotated at substantially the speed at which it is to be driven and may then be subsequently connected with the driving element.

I claim:

35 1. The combination with a driving shaft and a driven shaft of a clutch means comprising a driving element and a driven element, said driving element being rotatable by the driving shaft and said driven element being non-rotatably mounted on the driven shaft, an arcuate shaped flange portion connected with one of the elements and disposed concentric and in spaced relationship with the driven shaft, said flange portion terminating in shoulder portions, a radially extending peripheral flange portion connected with the other of said elements and terminating in shoulder portions, a radially extending offset flange portion connected with the element having the radially extending flange portion and disposed in spaced apart position with respect to said radially extending flange portion, said arcuate-shaped and radially extending flange portions being provided with frictional means adapted for engagement, one of said elements being movable for moving the frictional means into mutual engagement, said last named element being further movable for moving the offset flange portion into engagement with the arcuate-shaped flange portion subsequent to the engagement of the frictional means whereby a shoulder portion of the radially extending flange portion may be positioned for engagement with a shoulder portion of the arcuate-shaped flange portion, said last named element being further movable for moving the shoulder portion of the offset flange portion into engagement with a shoulder portion of the arcuate-shaped flange portion, whereby the elements may be retained in locked relationship.

70 2. The combination with a driving shaft and a driven shaft of a clutch means comprising a driving element being rotatable by the driving shaft and said driven element being non-rotatably mounted on the driven shaft, an arcuate-shaped flange portion connected with one of the elements and disposed concentric and in

spaced relationship with the driven shaft, said flange portion terminating in shoulder portions, a radially extending peripheral flange portion connected with the other of said elements and terminating in shoulder portions, a radially extending offset flange portion connected with the element having the radially extending flange portion and disposed in spaced apart position with respect to said radially extending flange portion, said offset flange portion having a shoulder portion, said arcuate-shaped and radially extending flange portions being provided with frictional means adapted for engagement, one of said elements being movable for moving the frictional means into mutual engagement, said last named element being further movable for moving the offset flange portion into engagement with the arcuate-shaped flange portion subsequent to the engagement of the frictional means whereby a shoulder portion of the radially extending flange portion may be positioned for engagement with a shoulder portion of the arcuate-shaped flange portion, said last named element being further movable subsequent to the engagement of the shoulder portions for moving said last named shoulder portions into further engagement and for moving the shoulder portion of the offset flange portion into engagement with a shoulder portion of the arcuate-shaped flange portion, whereby the elements may be retained in locked relationship.

3. The combination with a driving shaft and a driven shaft of a clutch mechanism comprising a driving element and a driven element, said driving element being rotatable by the driving shaft and said driven element being non-rotatably mounted on the driven shaft, one of said elements having arcuate-shaped and laterally extending peripheral flange portions disposed in spaced relationship with the driven shaft and comprising a lower flange portion and a higher flange portion, said flange portions terminating in shoulders, a radially extending peripheral flange portion connected with the other of said elements and having shoulders, one of said elements being movable for moving the radially extending flange portion into engagement with the higher flange portion, said last named element being further movable for moving the radially extending flange portion into engagement with the lower flange portion whereby said radially extending portion may be positioned for abutting engagement with the arcuate-shaped flange portion, one of said elements having an inclined peripheral surface, the other of said elements having a laterally extending peripheral flange portion provided with an inclined inner surface, said inclined surfaces being positioned for engagement prior to the engagement of the radially extending flange portion with the arcuate-shaped flange portion, for operatively connecting the driven element with the driving element.

4. The combination with a driving shaft and a driven shaft of a clutch mechanism comprising a driving element and a driven element, said driving element being rotatable by the driving shaft and said driven element being non-rotatably mounted on the driven shaft, one of said elements having a pair of arcuate-shaped and laterally extending peripheral flange portions diametrically opposed with respect to each other and terminating in shoulders, a pair of radially extending peripheral flange portions connected with the other of said elements and terminating

in shoulders, said element having the arcuate-shaped flange portions being provided with an inclined peripheral surface, laterally extending peripheral flange portions connected with the radially extending flange portions and provided with inclined inner surfaces, one of said elements being movable for moving the inclined surfaces into mutual engagement for frictionally connecting the elements, said last-named element being further movable for moving the radially extending flange portions into engagement with the arcuate-shaped flange portions and subsequently positioning said radially extending flange portions between the arcuate-shaped flange portions and in abutting relationship therewith for connecting the elements in interlocking relationship.

5. The combination with a driving shaft and a driven shaft of a clutch mechanism comprising a driving element and a driven element, said driving element being rotatable by the driving shaft and said driven element being non-rotatably mounted on the driven shaft, one of said elements having a pair of arcuate-shaped and laterally extending peripheral flange portions diametrically opposed with respect to each other and terminating in shoulders, a pair of radially extending peripheral flange portions connected with the other of said elements and terminating in shoulders, said element having the arcuate-shaped flange portions being provided with an inclined peripheral surface, a laterally extending peripheral flange portion mounted on the radially extending flange portions and longitudinally movable with respect thereto, said laterally extending flange portion being non-rotatable with respect to said radially extending flange portions and provided with an inclined inner surface, said laterally extending flange portions being movable for moving the inclined surfaces into mutual engagement for frictionally connecting the elements, one of said elements being subsequently movable for moving the radially extending flange portions into engagement with the arcuate-shaped flange por-

tions and subsequently positioning said radially extending flange portions between the arcuate-shaped flange portions and in abutting relationship therewith for connecting the elements in interlocking relationship.

6. The combination with a driving shaft and a driven shaft of a clutch mechanism comprising a driving element and a driven element, said driving element being rotatable by the driving shaft and said driven element being non-rotatably mounted on the driven shaft, one of said elements having a pair of arcuate-shaped and laterally extending peripheral flange portions diametrically opposed in spaced relationship and terminating in shoulders, each of said flange portions comprising a lower flange portion and a higher flange portion, a pair of diametrically opposed and radially extending peripheral flange portions connected with the other of said elements and having shoulders, one of said elements being movable for moving the radially extending flange portions into engagement with the higher flange portions, said last named element being further movable for moving the radially extending flange portions into engagement with the lower flange portions whereby said radially extending portions may be positioned for abutting engagement with the arcuate-shaped flange portions, said last named element being further movable for positioning the radially extending flange portions between the arcuate-shaped flange portions and in abutting engagement therewith, said element having the arcuate-shaped flange portions being provided with an inclined peripheral surface, laterally extending peripheral flange portions connected with the radially extending flange portions of the other element and provided with an inclined inner surface, said inclined surfaces being positioned for engagement, prior to the engagement of the radially extending flange portions with the arcuate-shaped flange portions, for operatively connecting the driven element with the driving element.
